[57] CLAIM

The ornamental design for a stackable bar stool, as
shown and described.

DESCRIPTION

FIG. 1 is a perspective view of a stackable bar stool,
showing my new design;

FIG. 2 is a top view of the stool;

FIG. 3 is an elevational view facing one side of the
stool; and,

FIG. 4 is a rear elevational view thereof.

Fig. 1.

Fig. 2.

FIG. 4.

FIG. 3.
